Julian G. Samuels, St. Louis, Mo.

To all whom it may concern:

Be it known that I, Julian G. Samuels, a citizen of the United States, residing at 6371 Waterman Avenue, St. Louis, in the city of St. Louis and State of Missouri, have invented a new, original, and ornamental Design for a Shoe or Article of Analogous Nature, of which the following is a specification, reference being had to the accompanying drawing, forming a part thereof.

In the accompanying drawing Figure 1 is a view, in plan, of a shoe showing my new design,

and Fig. 2 is a side elevational view of the shoe.

The dominant feature of my design resides in the ornamental effect produced by a series of variegated panels formed in the tip, bow, and quarters.

I claim:

The ornamental design for a shoe or article of analogous nature, substantially as shown and described.
